OF D 16,730

Design No. 16,730, dated June 8, 1886.

UNITED STATES PATENT OFFICE.

CANDACE WHEELER, OF NEW YORK, N. Y.

DESIGN FOR THE DECORATION OF CURTAIN FABRICS, &c.

SPECIFICATION forming part of Design No. 16,730, dated June 8, 1886.

Application filed April 28, 1886. Serial No. 200,481. Term of patent 7 years.

To all whom it may concern:

Be it known that I, CANDACE WHEELER, a citizen of the United States, residing in the city, county, and State of New York, have 5 invented and produced a new and original Design for the Decoration of Curtains, Draperies, &c., of which the following is a specification, and which is illustrated in the accompanying photograph.

10 The design consists in the representation of ribbons A, irregularly looped together or entwined, as shown, and interspersed at regular intervals with representations, as shown at B C, of sea-shells, the entire design being con-

tinued over the whole surface to be decorated 15 therewith.

I claim—

The design for curtains, draperies, and like fabrics, the same consisting of a curtain, drapery, or like fabric having upon its surface 20 the representation of the conventionalized entangled ribbons and the regularly interspersed shells, substantially as described and shown.

CANDACE WHEELER.
